V. E. MALATO.

SYRINGE FOR HYPODERMIC INJECTIONS.

APPLICATION FILED OCT. 19, 1914.

1,181,534.

Patented May 2, 1916.

UNITED STATES PATENT OFFICE.

VITTORIO EM. MALATO, OF MILAN, ITALY.

SYRINGE FOR HYPODERMIC INJECTIONS.

1,181,534.

Specification of Letters Patent.

Patented May 2, 1916.

Application filed October 19, 1914. Serial No. 867,507.

To all whom it may concern:

Be it known that I, VITTORIO E. MALATO, doctor of medicine, a subject of the King of Italy, and resident of 18 Via Durini, Milan, Italy, have invented new and useful Improvements in Syringes for Hypodermic Injections, of which the following is a specification.

My invention relates to improvements in 10 syringes for hypodermic injections.

The said improvements have for their object an automatic and instantaneous regulation of the pressure inside the syringe, another object is the absolute sterilization and 15 disinfection of the instrument, and further objects are a rational and regular mode of use of the syringe, and simplicity of construction.

The new means embodied in said improved 20 syringe to attain the above mentioned objects are hereinafter described.

An open tubular piston has at its outer end a cavity for an air-filter. Above said cavity there is a hole, provided on a plane 25 surface and particularly adapted to enter into a close contact with the thumb, so that the latter can be used as an automatic valve. A means is provided to act as a brake for the piston. This brake has for its object to 30 produce, while using the syringe, a sufficient reaction on the thumb for the purpose of maintaining the efficiency of same while acting as a regulating valve.

As regards the construction, metallic 35 means are provided for combining with one another the parts of the syringe which are preferably made out of glass.

In the annexed drawings are represented, 40 by way of example, three different constructional forms of the syringe.

Figure 1 shows an elevational view partly in section and to a scale larger than full size, of a syringe of the siphon type, embodying my said improvements. Fig. 2 45 shows a sectional view of a second form of construction of a syringe of the same type as Fig. 1. Fig. 3 shows a sectional view, partly in elevation of a simple syringe. Fig. 4 shows a plane view of some details of 50 construction. Fig. 5 is a detail hereinafter referred to.

In the different figures, like numerals designate like parts.

The body or cylinder of the syringe is 55 made of glass —1— and has at its upper open end a flange —2—, and terminates at

its lower end in a nozzle 3. A glass-piston —4— is open at both ends, and terminates at the top end with a cavity or chamber 6 for asbestos wool or the like which forms an air-filter —7—. This chamber is preferably comprised between two necks —5— formed in the glass.

8 is a regulating hole for the pressure inside the syringe, and is bored on a surface 65 —9— either plane or slightly convex. To this surface is applied the thumb for the purpose of acting as an instantaneous valve on the hole —8—.

Piston —4— and cylinder —1— are respectively ground outside and inside and they enter and slide airtight one into the other.

The piston brake is made up of one or two springs —10— mounted on a support. 70 Said support comprises a collar —11— provided with two arms on which rest pieces —12—. On the front of pieces —12— are fixed the springs —10— which are shaped as seen in Fig. 4. This support device is 75 fitted on the syringe by a loose collar —11— against the flange —2— so forming an extending flange for the flange —2—, while springs —10— are arranged tangentially to piston —4—. Underneath flange —2— is 80 fitted another collar with arms —13— and through the arms of the collars —11— —13— and the pieces —12— are bored in one line, holes —15— for the fixing screws —14—. The screw threads for said screws 85 are formed in the holes —15—.

16 are centering pins for collars —11— and —13—.

17 are regulating thumb-screws, which enter the pieces —12—, their heads —18— being set against the free ends of springs —10— so as to keep the latter pressed against piston —4—.

In the forms of construction shown in 100 Figs. —1— and —2— the siphon chamber is made up of countertube —20— which is fitted around cylinder —1—. It is provided with a flange —2'— which has the same function as flange —2— in Fig. 3.

Tube —3'— may constitute a natural tail 105 or nozzle of cylinder —1— or as shown in Fig. 2. It may comprise a separate tube fitted to the short nozzle of the cylinder.

Tube 21 is loosely mounted around the nozzle 3' and co-acts with same to form 110 the siphon chamber, while its lower portion is shaped in cross-section as not to cor-

respond with its seating in tube 3, so as to leave a free passage for the injection liquid to pass to the nozzle 3, as will be seen at Fig. 5 which is a section through Figs. 1 5 and 2 at A—A.

In the siphon-forms, tubes —3— to receive the holed needle (cannula) are formed at the end of countertube —20—.

While operating the syringe, the thumb 10 is kept constantly at the top of the piston and upon the surface —9— above hole —8— for the purpose of regulating instantly at will the pressure inside the cylinder.

For the purpose of sterilizing the injection liquid by heat, the hole of the needle, 15 may be closed by pinning into it a piece of cork.

Having now particularly described and ascertained the nature of my invention and 20 in which way the same has to be performed I declare that what I claim is:

1. A syringe for hypodermic injections comprising in combination a glass cylinder open at both ends, an open tubular piston 25 fitted in said cylinder, a chamber at the top of said piston in direct communication with the interior of the piston, a flat surface at the top of said chamber, air-filtering substance in said chamber, a hole in said flat 30 surface setting the filter-chamber in communication with the open air and adapted to the application of the thumb for the purpose of regulating the pressure in the interior of the cylinder.

35 2. A syringe for hypodermic injections comprising in combination a glass cylinder open at both ends, a flange on one end of the cylinder, an open tubular piston fitted in said cylinder, a chamber at the top of said 40 piston in direct communication with the interior of said piston, a flat surface at the top of said chamber; a hole in said flat surface setting the filter-chamber in communication with the open air, a metallic collar 45 with side arms resting on the flange of said

cylinder, a metallic collar with side arms resting underneath the flange of said cylinder, two fixing pieces on said first collar, screws connecting said collars and fixing pieces, flat springs fixed with one end to 50 said fixing pieces and resting with the other end against the piston, adjusting screws in said fixing pieces and with their heads set against said springs.

3. A syringe for hypodermic injections 55 comprising in combination a glass-cylinder open at both ends and having at the bottom a nozzle, a flange on one end of the cylinder, a cylindrical countertube fitted around said cylinder, a nozzle at the bottom of the countertube to take a cannula, a tubular piece surrounding the nozzle of the first cylinder and mounted inside the countertube so as to form a siphon-like communication between the first and the second mentioned nozzles, 60 an open tubular piston fitted in said cylinder, a chamber at the top of said piston in direct communication with the interior of said piston, a flat surface at the top of said chamber, a hole in said flat surface setting 65 the filter chamber in communication with the open air, air-filtering substance in said chamber, a metallic collar with side arms resting underneath the flange of said cylinder, a metallic collar with side arms resting 70 on the flange of said cylinder, two fixing pieces resting on the last named collar-arm, connecting screws of said collars and said fixing-pieces, flat springs fixed with one end to 75 said fixing pieces and resting against said piston, adjusting screws in said fixing pieces and with their heads set against said springs.

In testimony whereof I have signed my name to this specification in the presence of 80 two subscribing witnesses.

VITTORIO EM. MALATO.
